CLAIM

I claim the ornamental design for a vehicle request device as shown, i.e. a device for requesting a vehicle, such as a taxi, to a location associated with the device.

DESCRIPTION

FIG. 1 is a perspective view showing the front of a vehicle request device.

FIG. 2 is a perspective view showing the rear of the device.

FIG. 3 is a top view of the device.

FIG. 4 is a front view of the device.

FIG. 5 is a bottom view of the device.

FIG. 6 is a rear view of the device; and,

FIG. 7 is a side view of the device, the left and right side views being the same.

The device may be fixedly secured to a surface and arranged to provide feedback to users as to the status of any vehicle requests.
